United States Patent Office.

DAVID B. HAY, OF DAYTON, OHIO.

Letters Patent No. 102,937, dated May 10, 1870.

IMPROVED SCAFFOLD-SUPPORTER.

The Schedule referred to in these Letters Patent and making part of the same.

To all whom it may concern:

Be it known that I, DAVID B. HAY, of Dayton, in the county of Montgomery and State of Ohio, have invented an Improved Scaffold-Support; and I do hereby declare that the following is a full, clear, and exact description thereof, reference being had to the annexed drawings making part of this specification, in which—

Figure 1 is a perspective view.

Figure 2 is a vertical longitudinal section.

Figure 3 is a perspective view, showing how the device may be used for raising or lowering a platform bodily.

Corresponding letters refer to corresponding parts in the several figures.

The nature of my invention consists in providing a device for supporting scaffolding, it being a band of metal, of a rectangular or other suitable form, beveled from its ends toward the center, where it is provided with a wedge-shaped cross-bar, as hereinafter more fully set forth.

To enable those skilled in the art to make and use my invention, I will proceed to describe its construction and operation.

A, in the drawings, represents a continuous band of metal, which may be made of a rectangular form, as shown, or any other suitable shape. It is to be made slightly angled or curved, as shown in fig. 2, sloping from its ends toward the center, where it is provided with a wedge-shaped cross-bar, A', the base of which is at the convex side of the band. This cross-bar di-

vides the opening into two equal spaces, each of which is to be of such dimensions as to be capable of receiving an ordinary upright used in scaffolding.

This device may be used in the following manner:

One is slipped over each upright of a scaffold in such a manner that the base of the wedge-shaped cross-bar is on the under side. It is apparent that it will grasp such upright at any desired point where the platform is needed. This latter may then be formed by placing one end of a cross-beam upon the protruding part of the device, which, by reason of its curved or angled form, will incline toward the upright, and thus prevent the beam from slipping off, and extend the other end across to the wall, where it may be supported in the usual manner, and laying boards upon these beams. To afford a more secure platform, the outer end of each beam may be secured in the protruding part of the device.

Having thus described my invention,

What I claim, and desire to secure by Letters Patent, is—

The device herein described, substantially as and for the purpose set forth.

In testimony whereof I have signed my name to this specification in the presence of two subscribing witnesses.

D. B. HAY.
